OPERATING HANDLE FOR ROTARY TOOLS

Karl E. Queitzsch, York, Pa.

Application November 29, 1947, Serial No. 788,952

7 Claims. (Cl. 81—61)

1

This invention relates to operating handles for rotating tools such as sockets for nuts, machine screw heads and the like, or screw driver implements of any desired character.

An important object of the invention is the provision of an operating handle of this character which will provide, in at least one relative position of tool and handle, a positive driving connection between the tool and handle and will also provide through a substantial angular relation of the tool and handle a reversible ratchet connection.

Another object of the invention is the provision of a structure of this character which is simple to manufacture comprising a minimum number of parts which can be readily and durably constructed.

These and other objects I attain by the construction shown in the accompanying drawings wherein for the purpose of illustration I have shown a preferred embodiment of my invention and wherein:

Figure 1 is front elevation of a tool handle constructed in accordance with my invention;

Figure 2 is a side elevation of the handle illustrating various positions which may be assumed by the tool attaching tang;

Figure 3 is a section on line 3—3 of Figure 1;

Figures 4 and 5 are respectively a plan view and an elevation of the swivel head;

Figure 6 is an enlarged section on line 6—6 of Figure 2;

Figure 7 is a section on line 7—7 of Figure 6 but with the cage rotated 180 degrees from its position in Figure 6;

Figure 8 is a fragmentary sectional view showing the pawl engaged to prevent relative rotation of the head and handle;

Figure 9 is a similar section showing the pawl engaged for ratchet connection of the head and handle; and

Figure 10 is a section on line 10—10 of Figure 4.

Briefly stated, my invention contemplates an improved tool-operating handle in which a selected direction of one-way ratcheting action is available for rotating a tool on a tool-actuating axis, by means of universal-action parts, this ratcheting action may be achieved over a plurality of angular relationships between the handle axis and the tool-actuating axis, extending from substantially 90° to substantially an aligned relation of these axes. For the aligned or straight-on relation of the handle axis and of the tool-actuating axis, I provide mechanism for locking the handle to the tool-actuator so that in this par-

2

ticular relation no ratchet action can take place, as in an ordinary wrench.

Referring now more particularly to the drawing the numeral 10 designates a handle one end of which is formed as a hemi-spherical socket element 11. Rotatably engaged with socket element 11 is a cage 12 having a sector or quadrant slot 13 one terminal of which is the axis of socket element 11 perpendicular to said element. Cage 12 combines with element 11 to provide a ball-retainer spherical socket housing, spherical head 14 having at one pole thereof a tang 15 projecting through slot 13 and adapted as at 16 for the interchangeable reception of rotary tools such as socket wrench 17 shown in dotted lines in Figure 2. As at present shown socket element 11 is circular in cross section and has an annular groove 18 receiving a chordal pin 19 mounted in cage 12 and serving to connect the cage and socket element while permitting relative rotation thereof. The cage is yieldably held in either of two 180° spaced positions by a spring pressed detent 20 carried by element 11 and engageable in sockets 21 in the cage.

The sphere 14 has longitudinal grooves 22 and 23, the groove 22 beginning and ending at a point adjacent the pole of the sphere bearing tang 15 and having its central portion 22a (that portion thereof traversing the other pole of the sphere) deepened for a purpose presently to appear. Grooves 23 begin at the same latitude as groove 22 and terminate adjacent said other pole and preferably short of communication with one another or groove 22 as shown.

Pivotedly mounted at 24 in a slot 25 in socket element 11 is a pawl 26 having a single ratchet rib 27 disposed in a general plane including the axis of tang 15. This rib has a depth at least that of the deeper portion 22a of groove 22 and a width providing a fairly snug fit thereof in grooves 22 and 23. One side face 28 of the rib is perpendicular for the full depth of the rib while the other wall 29 is perpendicular for a distance equal to the depth of the rib minus the depth of grooves 23 and the shallow portions of groove 22 and is connected with the outer face of the rib by a sloping wall 30.

It will be obvious that when the head 14 is positioned with its axis in longitudinal alignment with the axis of the handle 10, as shown in solid lines in Figures 1, 2 and 6, the grooves 23 and shallow portions of groove 22 are out of the zone of coaction with rib 27, and the latter may enter only the deep portion 22a of groove 22. When it does so, because of the depth of the

groove, both walls 28 and 29 of the rib are brought into opposition to the walls of groove 22a as shown in Figure 8, and the handle 10 and sphere 14 with its tang and applied tool are locked against relative rotation and the tool operates as a fixed screw driver or wrench. When, however, the position of the axis of the sphere is altered (within its range of displacement permitted by the sector or quadrant slot 13), as suggested by the positions A and B of Figures 2 and 10 3, the ratchet rib 27 is engageable only in the shallow portions of groove 22 and in grooves 23. Due to the depth of these grooves, propelling engagement between the pawl and sphere will occur in one direction only and a ratchet action 15 results. Since the sector or quadrant slot 13 is in a general plane normal to a plane including the axis of the cage 12 and retaining sockets 21, the position of head 14 is reversed with relation to the pawl when the cage is shifted from one 20 to the other of its 180° positions, thereby reversing the ratchet action.

It will be seen that I have described a relatively simple device permitting a selected direction of one-way ratcheting action, with extensive angular freedom (in the nature of limited universal action) between an operating handle and the axis of a tool actuator that is rotated thereby. With my construction, the handle is free to assume any one of a variety of universal-action relationships with the tool-actuator axis, and there is no locking against sliding movement within slot 13, so that the universal-action may be used in a single ratchet-action stroke, if desired. However, when the tool is employed in the aligned or straight-on relation, the handle 10 is locked against rotation with respect to the tool actuator 15 (by virtue of pawl faces 28-29 riding the deep part 22a of ratchet slot 22), and no ratchet action is available.

Since the construction shown is obviously capable of considerable modification without departing from the spirit of my invention I do not wish to be understood as limiting myself to the construction herein disclosed except as hereinafter claimed.

I claim:

1. In combination, a handle, a cage carried by one end of said handle and forming with said end of said handle a ball-retainer socket, said cage including a wall having an arcuate slot therein converging toward the axis of said handle, a spherical ratchet head mounted in said socket and including a tool-attachment tang projecting through the arcuate slot in said cage, and coacting elements including a pawl retained by said head and handle and having ratcheting engagement with said head throughout a substantial angular displacement of the axis of said tang with respect to the axis of said handle, said pawl having non-rotating locking engagement with said head for the aligned relation of the tang and handle axes.

2. In combination, a handle, a cage selectively rotatably mounted upon one end of said handle and forming with said end of said handle a ball-retainer socket, said cage including a wall having an arcuate slot therein and said slot extending over a substantial arc passing through and in alignment with the axis of said handle, a spherical head mounted in said socket and having a radially extending tool-attachment tang projecting through said arcuate slot, ratchet means including a pawl carried by said handle, said pawl being operatively engageable with

10 said head throughout an extensive angular range of displacement of the axes of said handle and of said tang, said pawl being reversibly engageable with said head upon relative angular movement of said cage and handle between two positions on opposite sides of the plane of said slot and of the cage axis, and means coacting between said cage and said handle for retaining said cage and handle in a selected one of said two positions.

3. In combination, a handle including a cage mounted upon one end of said handle and forming with said end of said handle a socket, said cage including a wall having a longitudinal sector slot therein, a spherical head mounted in said socket and having a radially extending tool-element-attaching tang projecting through said slot, said slot extending through and in alignment with the axis of said handle, coacting key elements on said head and handle preventing relative rotation of said head and handle about their respective axes when the axes of said head and handle are in a longitudinally aligned relation and having ratchet engagement with one another through an extensive angular displacement of said axes from such aligned rotation.

4. In combination, a handle including at one end a fixed concave socket surface, a cage rotatably engaged with said end of said handle and extending over said socket surface to form a ball-retainer socket, said cage having a sector slot longitudinal to the major axis of the socket, and extending at one part thereof in alignment with said axis, means to secure the cage and handle against relative rotation in either of two angularly spaced relative positions, said two relative positions being on opposite sides of a plane including both the slot and said axis, whereby the position of the slot with relation to the socket is reversed by movement of said cage from one to the other of said positions, a spherical head rotatably mounted in said socket and including tool-driving means projecting radially and through said slot, and pawl means carried by said handle and reversibly engageable with said head by movement of the cage from one to the other of said positions.

5. In combination, a handle including a spherical socket having an arcuate slot therein, a sphere in said socket and including at one pole a tool-engaging tang projecting through said slot, said sphere further having a plurality of longitudinal grooves one of which has a central section traversing the other pole of the sphere and of greater depth than the end portions of said groove and of the remaining grooves, and a pawl element fixed with relation to the handle when engaged in the central portion of said groove and having ratchet engagement with said sphere when engaged with the ends of said groove or with remaining grooves.

6. In combination, a ball-head member including a ball head and a tool-attachment tang projecting radially from said ball head, operating means for driving said tang and including a handle, retaining means carried by said handle and embracing said ball head in free-swivelling relation with said ball head, said retaining means having an arcuate slot through which said tang projects and over the arcuate extent of which said ball-head member may be angularly adjusted with respect to said handle, said slot extending over a substantial angular arc passing through alignment with the axis of said handle, means for ratcheting said handle relatively to

said ball-head member in a plurality of positions of said handle relative to said ball-head member, said positions being displaced from the position of axial alignment of said handle and of said tang, and means carried by said head and denying ratchet action between said head and handle in said aligned position.

7. In combination, a ball-head member including a ball head and a tool-attachment tang projecting radially from said ball head, operating means for driving said ball-head member and including a handle, housing means for said ball head at the end of said handle and in free-swivelling relation with said ball head, said housing means having an arcuate slot through which said tang projects and over the arcuate extent of which said ball-head member may be angularly adjusted with respect to said handle, said slot extending over an effective arc passing through alignment with the axis of said handle 20

and extending to at least substantially the 90-degree relation between said tang and said handle, and ratchet means retained between said handle and ball-head member for driving said ball head and tang by said handle in a plurality of angular positions of said ball head and tang in said housing as permitted by said angular slot.
